UNITED STATES PATENT OFFICE.

BERNARD D. WILLIS, OF CHICAGO, ILLINOIS, ASSIGNOR TO AUTOMATIC ELECTRIC COMPANY, OF CHICAGO, ILLINOIS, A CORPORATION OF ILLINOIS.

AUTOMATIC TELEPHONE SYSTEM.

1,314,778.

Specification of Letters Patent.

Patented Sept. 2, 1919.

Application filed February 28, 1916. Serial No. 80,919.

To all whom it may concern:

Be it known that I, BERNARD D. WILLIS, a citizen of the United States of America, and a resident of Chicago, county of Cook, 5 and State of Illinois, have invented certain new and useful Improvements in Automatic Telephone Systems, of which the following is a specification.

My invention relates to automatic telephone systems and has particular reference to such systems as comprise two or more exchanges interconnected by trunk lines. More specifically my invention is concerned with trunk circuits connecting exchanges between which certain of the connections may be established by operators, such as private branch exchange operators; or which comprise, in part at least, measured service lines provided with meters. 10 In systems of the above general character, it has been found desirable, in inter-exchange connections, to operate the automatic switches in the distant exchange over so-called simplex circuits superimposed upon the connecting trunk lines. It is desirable also, or even necessary, to provide means associated with the inter-exchange trunk lines, whereby supervisory signals may be operated to notify operators of the response 15 of called subscribers. Furthermore, where measured service is given, means must be provided for actuating the meters associated with calling lines at the proper time.

It is the principal object of my invention 20 to provide a trunk circuit having a superimposed simplex circuit for operating purposes; and having, in addition, facilities for controlling supervision at an operator's position, or for controlling subscribers' meters or similar devices.

A further object of my invention is the provision of a trunk circuit of the above description adapted for two way service.

Further objects of my invention relate 25 to circuit improvements of various kinds whereby the above features are incorporated into well known types of apparatus to form a complete and efficient system.

To accomplish the foregoing and other 30 useful ends my invention comprises means which will be hereinafter fully explained, reference being had to the accompanying drawings, in which Figure 1 shows a diagrammatic layout of the telephone system 35 chosen to illustrate my invention, while Figs.

2, 3, 4, and 5, taken in order with the lines at the ends thereof in alinement, represent a complete circuit connection between two subscribers in such system.

Referring now to Fig. 1, the manual telephones A² terminate in answering jacks J and multiple jacks J² upon the private branch exchange switchboard M. The jacks J² are terminals of outgoing trunk lines extending to a group of selector switches E at 60 the exchange X.

The automatic telephones A' terminate at the exchange X in individual line switches C², which may be given access in the well known manner to additional selector 70 switches E. The selectors E, associated with both manual and automatic lines, have access to repeaters F which are arranged to transmit impulses over simplex circuits superimposed upon the trunk lines T to control automatic selectors E² and connectors H² in the exchange Y.

The automatic telephones A³, through the medium of their individual line switches C', and the manual telephones A⁴, through the medium of the private branch exchange switchboard M', have access to selectors E' at exchange Y, whereby connections may be extended to repeaters F' to control automatic selectors E³ and connectors H' over 75 80 85 the same trunk lines T.

Referring to Fig. 2, there is shown at A a subscriber's substation which may be of any suitable type and as herein represented comprises a receiver 2, transmitter 3, switch 90 hook 6 and ringer 4. The line conductors 10 and 11 terminate in a private branch exchange switchboard where they are provided with line and cut-off relays 8 and 9, answering jack J, and one or more multiple jacks J².

The private branch exchange switchboard may be provided with a plurality of cord circuits such as the one indicated by reference character O. Cord circuit O comprises essentially the answering and calling plugs 100 P and P', the supervisory lamps 19 and 21, controlled, respectively, by relays 15 and 18, listening key K', ringing key K², and calling device key K. Relay 18 is a polarized relay the operation of whose armature 105 depends upon the direction of current flow in the relay windings.

Reference character 20 indicates a calling device which is preferably common to a plurality of cord circuits and adapted to be 110

bridged across any one of them through the medium of the associated key K. The calling device may be of any suitable type, such, for example, as the one shown in British patent 5 to S. G. S. Dicker, No. 29654 of 1910.

An outgoing trunk line extends from the jack J' at the private branch exchange to the main exchange X, where it terminates in the selector switch E which, as represented herein, is of the same general type of selector switch as is disclosed in U. S. Letters Patent No. 815,321, granted March 13, 1906, to Keith, Erickson and Erickson; being, however, of the particular type disclosed in British patent to the Automatic Telephone Manufacturing Company, No. 2543 of 1914. Among other details the selector E comprises a bank of contacts arranged in horizontal rows or levels and 20 adapted to be engaged by a set of wipers 31, 32, and 33, carried upon a shaft (not shown) which has a vertical movement controlled by the vertical magnet 23 and a rotary movement controlled by the rotary magnet 24. 25 The operation of the various parts of the switch is controlled by the double wound line relay 22. Means for restoring the switch to its normal position is provided in the release magnet 25 which, upon energizing, withdraws the retaining pawls from the shaft. The off normal contacts 34 and 40 are closed only when the shaft is raised one or more steps from its normal position. Relays 27 and 29 are slow acting, *i. e.*, they 30 are slow to release their armatures after their energizing circuits are broken. The selector E has access, through certain of its bank levels, to groups of trunk lines extending to the different line groups in exchange X; and, in addition, through a separate bank level, to a group of trunk lines extending to exchange Y. One trunk line in this latter group is shown extending from the bank contacts 31^a and 33^a in Fig. 2, by 40 change X; and, in addition, through a separate bank level, to a group of trunk lines extending to exchange Y. One trunk line in this latter group is shown extending from the bank contacts 31^a and 33^a in Fig. 2, by 45 way of conductors 46 and 47, repeater F (Fig. 3), repeating coil I, jack J², conductors 87 and 88, jack J³ (Fig. 4), repeating coil Z, and repeater F' to connector H (Fig. 5). 50 The repeater F comprises a plurality of relays whose functions can best be described in connection with the detailed explanation. It may be mentioned at this time, however, that relay 55 is an electropolarized relay, it 55 being provided with a polarizing winding of high resistance and few turns. Current flowing in the polarizing winding is not of itself sufficient to operate the armature but is able to prevent such operation by the other 60 winding unless the current therein flows in the proper direction.

It will be seen that the trunk conductors 87-88 are looped through springs of jacks J² and J³ before connecting with the repeating coils associated with repeaters F and F'. 65

This is not, of course, necessary in carrying out the strictly automatic features of my invention but is found very convenient in practice. The jacks J² and J³ may be located, respectively, at toll boards in the X 70 and Y exchanges and are provided with the usual drops 57 and 90, and, in addition, with visual busy signals 59 and 89, and sleeve relays 58 and 91.

Repeater F', located in the exchange Y, 75 is in all respects similar to repeater F.

Conductors 77 and 79 are shown as extending to the connector H, which is of the general type of connector switch disclosed in U. S. Letters Patent No. 815,176, granted 80 March 13, 1906, to Keith, Erickson and Erickson; being, however, of the particular type disclosed in British patent to the Automatic Telephone Manufacturing Company, No. 2270 of 1914. The connector H comprises among other details a bank of contacts arranged in horizontal rows or levels and adapted to be engaged by a set of wipers 60, 61, and 62 carried upon a shaft (not shown) having a vertical movement controlled by 85 the vertical magnet 64 and rotary movement controlled by the rotary magnet 65. The usual side switch comprising the wipers 110, 111, 112, and 113 is controlled by the private magnet 70 in the well known manner. The 90 operation of the various parts of the switch is controlled by the double wound line relay 63. There is provided also a release magnet 68, a back bridge relay 66, a busy test relay 72, and a ringing relay 69, whose functions 100 are well known. Contacts 114 and 115 are closed only when the switch shaft has been raised one or more steps from its normal position. Relays 67 and 71 are slow acting, *i. e.*, they are slow to release their armatures 105 after their respective energizing circuits are broken.

While I have shown, for the sake of simplicity, the conductors 77 and 79 as extending directly to the connector H, it will be 110 understood that selector switches such as the selector E (Fig. 2) may be interposed between the repeater F' and the connector H in order to increase the capacity of the 115 system.

The connector switch H has access to a group of lines among which is the line extending to substation A³. The automatic substation A³ may be of any suitable type, it being only required that the controlling 120 impulses be sent by interrupting the line circuit rather than by grounding the line conductors. Such a substation is illustrated in British patent specification No. 2543 of 1914. 125

The individual line switch C', whose function is to extend the line of substation A³ when calling to an idle selector switch, is of the general type of line switch disclosed in British patent to R. W. James, No. 26301 of 130

1906; being, however, of the particular type disclosed in U. S. Letters Patent to F. Newforth, Jr., No. 13,901, reissued April 13, 1915. The line switch C' will have access to selector switches E' as is shown diagrammatically in Fig. 1 through the medium of which connections may be extended to other lines in the exchange Y or to lines in exchange X, as previously mentioned.

10 Before proceeding farther it will be advisable to return to the trunk circuit and explain certain details which it was not convenient to mention before. In Fig. 2 there is shown a set of multiple bank contacts denoted by reference characters 35, 36, and 37. These contacts may be located in the bank of a selector switch E which is accessible to line switches C² in exchange X (Fig. 1). In Fig. 3 there are shown two conductors, 77^a and 79^a, extending upward from the repeater F. These conductors are similar to conductors 77 and 79 (Fig. 4) and extend either to a selector switch or a connector switch depending on the capacity of exchange X. In Fig. 1, trunk lines such as the one represented in Fig. 3 by conductors 77^a and 79^a may be seen extending downward from repeaters F to selectors E³. The repeater F' (Fig. 4) is accessible to two groups of selector switches as shown clearly in diagrammatic drawing Fig. 1. This fact is indicated in Fig. 4 by the showing of two sets of multiple contacts numbered, respectively, 84—85—86 and 81—82—83. These 25 two sets of contacts correspond to the two sets shown at the right of Fig. 2.

30 For supplying current for operating and talking purposes I have shown a plurality of batteries, indicated by reference characters B, B³, and B⁴, each having its positive pole grounded. There are also shown two other batteries, B' and B², each having its negative pole grounded and whose functions will be fully described hereafter. The reference character Q indicates a busy signaling machine, whose function is well known.

35 Having given a general description of the apparatus, I will now describe the operations performed in the process of establishing a connection from the manual substation A² (Fig. 2) to the automatic substation A³ (Fig. 5). Since the automatic selectors, connectors, and other apparatus, herein represented, are in general well known in the art, and are fully described in the publications hereinbefore referred to, their operation will be described in a more or less general manner.

Upon the removal of the receiver at the 40 calling telephone A², the circuit of the line relay 8 is closed over a path which extends from ground G⁴ through the back contact of armature 14, line conductor 10, receiver 2, transmitter 3, spring 7 on hook 6, line conductor 11, armature 13 and its back contact,

and the relay 8 to the battery B⁴. The relay 8, upon energizing, closes the circuit to lamp 12 to indicate to the operator that a call has been received. The operator answers the call by inserting the plug P into the jack J, whereby the connection is completed between the line and the cord O. By the engagement of the third conductor of the plug P with the sleeve of jack J, the circuit of the cut-off relay 9 is closed in series with relay 16 of the cord. The relay 9, upon energizing, disconnects the line relay 8 from the line and connects the armatures 13 and 14 with their front contacts. The subscriber is now provided with talking current from the battery B⁴ through the two relays 15 and 17. The relay 15, upon energizing, opens the circuit of supervisory lamp 19 which was closed at another point when relay 16 energized. The operator then connects her talking set across the cord through the medium of the key K', and upon learning from the calling subscriber that a subscriber at the distant automatic exchange Y is wanted, she inserts the plug P' into the jack J' which is one terminal of a trunk line leading to the selector switch E at the distant exchange. By the engagement of the sleeve of plug P' with the sleeve of jack J' a circuit is closed from the grounded sleeve of the jack through sleeve relay 16^a and to battery B⁴. Relay 16^a, upon energizing, closes a contact in the circuit of calling supervisory lamp 21.

Upon the insertion of the plug in the jack, a circuit is closed for line relay 22 of the selector E in series with the polarized relay 18 of the cord circuit O. This circuit extends from ground through the lower winding of line relay 22, through normally closed contacts of relay 26, ring of jack J' and plug P', springs 41' and 42', relay 18, springs 42 and 41, tip of plug P' and jack J', through another pair of normally closed contacts of relay 26, and thence through the upper winding of line relay 22 to the battery B. The polarized relay 18 is energized and attracts its armature in the direction to close its contact, which lights the supervisory signal 21 over a circuit that is obvious. The line relay 22, upon energizing, closes the circuit of the slow acting relay 27. The relay 27, upon energizing, opens the circuit of the release magnet 25, and prepares a circuit for the vertical magnet 23 and the rotary magnet 24 in the well known manner. The operator now throws the key K, which separates springs 42 and 42' from springs 41 and 41', respectively, and substitutes for the former springs 43 and 43' which lead to the calling device 20. The relay 18 will now be in an open circuit and upon deenergizing will open the circuit of lamp 21. The relays of the selector are unaffected by the operation of 110

the key K, owing to the make before break contacts of said key. The operator now operates her calling device in accordance with the number of the desired station, which 5 will be assumed to be 220. Upon the operation of the calling device for the first digit 2, the impulse springs of the calling device are separated twice momentarily, each time breaking the circuit of the selector line re- 10 lay 22. Since the relay 27 is slow acting it does not deenergize during the momentary interruptions of its circuit by the deenergizations of the line relay 22. Therefore each time that the line relay deenergizes an im- 15 pulse of current is transmitted through the vertical magnet 23 and slow relay 29. The vertical magnet thus receives two impulses and operates to raise the shaft wipers 31, 32, and 33 two steps to a position opposite the 20 second level of bank contacts. The slow relay 29 is operated by these impulses to close the circuit to the test relay 28 which, upon energizing, locks up to ground G¹¹ and further prepares a circuit for the rotary 25 magnet 24. When the slow relay 29 deenergizes, after the first group of impulses have been completed, it closes a circuit to the rotary magnet 24 through interrupter springs 24^a and 24^b from ground G¹¹. Since the rotary magnet is provided with these interrupter springs, it begins to operate in a manner similar to a buzzer to advance the wipers step by step over the contacts of the level 48 which they have been raised by 30 the previous operations of the vertical magnet. This operation of the rotary magnet continues until the wipers find an idle trunk line. If the first trunk line is idle the relay 28 will be deenergized after the first 35 step and close the circuit to the switching relay 26 which, upon energizing, removes the relay 22 from the circuit and connects the line circuit with the wipers 31 and 33. If this trunk line is busy, however, the private wiper 32 finds the test contact with 40 which it engages provided with a guarding ground potential and another circuit is closed to maintain relay 28 energized before its circuit is broken by the energization of 45 the rotary magnet. This last circuit extends from ground upon the test contact to the private wiper 32 through the middle and front springs of relay 28 thence through said relay 28 to the battery B. The relay 50 28 is thus held energized and prevents the switching relay 26 from energizing. From the foregoing it will be clear that when the wipers 31, 32, 33 arrive at idle trunk contacts the controlling relay 28 is deenergized 55 and closes a circuit to switching relay 26. This circuit extends from ground G¹¹ through springs 30, springs 24^b, off normal contact 40, springs 39 and said relay 26 to battery B. As before stated the switching 60 relay 26, upon energizing, disconnects the 65 relay 22 and switches the line circuit to the wipers 31 and 33 which extends the connection to the line relay 44 of the repeater F, which relay, upon energizing, closes a circuit to slow relay 45. Relay 45, upon energizing, supplies a holding ground over the release trunk conductor 48 to the switching relay 26. The energizing circuit for the line relay 44 of the repeater F extends from ground G¹³ through the lower winding of 70 said relay 44, contact springs 116 and 117, conductor 47, wiper 33, contact springs 171 of relay 26, ring of jack J' and plug P', springs 42' and 43', calling device 20, springs 43 and 41, tip of plug P' and jack 75 J', contact springs 170 of relay 26, wiper 31, conductor 46, springs 118 and 119 of relay 49, and the upper winding of line relay 44 to battery B. The line relay 44, upon energizing, prepares a circuit for slow relay 49 at springs 120 and closes a circuit for release relay 45, as before mentioned, extending from ground G¹³ through springs 121 and said relay 49 to the battery. Relay 45 at its springs 122 provides the before mentioned holding ground to the selector switching relay 26 over a path extending from ground G¹² through contact springs 122, release trunk conductor 48, wiper 32, springs 39 of relay 28, thence through relay 26 to 80 the battery B. The relay 56 energizes at this time over a circuit extending from ground G¹² through springs 122, along conductor 127, springs 128 and the said relay 56 to the battery B. 85 The relay 56, upon energizing, removes the drop relay 57 from the trunk line by opening contacts 129 and 130 and lights the busy lamp 59 over a circuit which extends from ground G¹¹ through springs 131 and the 90 lamp 59 to the battery B. A further result of the energization of relay 45 is the shifting of spring 123 out of contact with spring 124 and into engagement with spring 125 thereby completing a circuit for slow acting 95 relay 49 which extends from the non-grounded pole of the battery B through said relay 49, springs 120 of relay 44, springs 125 and 123, along conductor 126 to the junction of repeating coil windings I² and I⁴, thence over both windings I² and I⁴ in 100 multiple, springs of jack J², line conductors 87 and 88 in multiple, springs of jack J³ (Fig. 4), windings Z² and Z³ of repeating coil Z in multiple to their junction, thence 105 along conductor 102, springs 103 and 104 of relay 101 of repeater F', conductor 106, relay 96, springs 108 and 109 to ground G¹⁶. This circuit as traced includes relay 49 of repeater F (Fig. 3) and relay 96 of repeater F' (Fig. 110 4). The relay 49 is so constructed and adjusted that it will not operatively energize at this time and it requires current of greater strength than that furnished by the 115 battery B to enable it to pull up its arma- 120 125 130

ture. The relay 96 energizes and upon doing so separates springs 129 and 130 and forces spring 129 into contact with spring 131. A circuit is then closed which includes slow relays 97 and 99. This circuit extends from ground G^{18} through springs 129 and 131 and relays 97 and 99 in multiple to the battery B^3 . A further result of the energization of relay 96 is the closure of springs 132 thereby bridging the impedance 93 in series with the upper winding of electro-polarized relay 94, across the conductors 77 and 79 leading to the connector H (Fig. 5). The relays 97 and 99 both energize over the circuit as above traced. Relay 99, upon energizing, forces springs 133 into contact, thereby preparing a circuit for slow relay 95. A further result of the energization of relay 99 is the closure of a circuit extending from ground G^{19} through springs 134, 135, and 136 and the lower winding of the electro-polarized relay 94 to the battery B^3 . Both windings of the said relay 94 now carry current which flows in opposite directions and they partially neutralize each other, there is therefore no resultant attraction of the armature. A still further result of the energization of relay 99 is the provision of ground upon the private bank contacts of selectors (not shown) which are adapted to seize repeater F' for the purpose of setting up a connection in the opposite direction. This last mentioned circuit extends from ground G^{19} through springs 134 and 135 to a point 137 thence over two paths, one path extending to private contacts 85 and 82 and multiples thereof, as above stated; the other path extending from said point 137 along conductor 138, contacts 139 of relay 91 and the cut-off relay 92 to battery B^3 . The relay 92, upon energizing, removes, by the opening of contacts 140 and 141, the drop 90 from across the trunk line conductors 87 and 88. By the closure of its springs 142 the circuit to the busy lamp 89 is completed. This circuit extends from ground G^{20} through springs 142 and said lamp 89 to battery B^3 . The slow relay 97, upon energizing, forces the springs 143 and 144 out of contact with springs 145 and 146 and into contact with springs 147 and 148, respectively. The result secured thereby is that the repeating coil windings Z^2 and Z^4 are disconnected from the selector bank contacts 81 and 86 and their multiples and are connected instead to the line conductors 77 and 79 leading to the connector H. By this arrangement it is seen that repeating coil Z^2 , condenser C⁶ and repeating coil Z^4 are now in multiple with impedance 93 and upper winding of relay 94 across the trunk conductors 77 and 79.

As hereinbefore stated, when relay 96 energized a bridge comprising the impedance 93 and upper winding of relay 94 was com-

pleted across the trunk to the connector line relay 63, whose complete circuit now extends from ground through the lower winding of said line relay 63, contacts of springs 147 and 148, line conductor 79, springs 132 70 of relay 96, upper winding of relay 94, impedance coil 93, return line conductor 77, springs 149 and 150 and the upper winding of the line relay 63 to the battery B^3 . The line relay 63 is energized over this circuit 75 and operates to close a circuit to the release relay 67 which extends from ground G^{21} through spring 151 and its front contact, and relay 67 to the battery B^3 . Relay 67, upon energizing, opens the circuit of 80 the release magnet 68 at springs 152 and 153 and forces spring 153 into contact with spring 154 thereby preparing a circuit for the vertical magnet 64. A further result of the energization of relay 67, is the 85 closure of springs 155 thereby supplying ground G^{22} along conductor 78 which is without function in the layout herein illustrated. It is, however, well understood by those versed in the art that I may have the 90 trunk line conductors terminate in a selector switch such as the switch E instead of leading direct to the connector as herein shown. In that event the ground G^{22} over release conductor 78 would maintain the selector 95 in its operated position after the connector has been selected. In this connection it is well to note again that I may provide a plurality of selectors between the repeater F' and connector H, thus increasing the 100 capacity of the system without deviating from the principles of my invention. The switching operations up to this point were responsive to the first digit called by the operator at the cord circuit O.

The operator now operates the calling device for the second digit 2, thereby causing the line relay 44, of repeater F, to deenergize twice momentarily. The relay 45 being slow acting, remains in its energized 110 position during the momentary interruptions of its circuit, so that each time the line relay 44 deenergizes and separates the springs 120 the circuit including relay 49 of repeater F and relay 96 of repeater F' 115 is momentarily broken. Relay 49 as before stated does not operatively energize and is provided with a copper slug for the purpose of reducing its impedance to a minimum while the impulses are being 120 transmitted therethrough over the simplex circuit to the distant repeater F'. Relay 96 of repeater F', responds to the momentary interruptions of its circuit and is momentarily deenergized a number of times to repeat impulses to the connector H. The relay 96, at each deenergization, opens the circuit of relays 97 and 99 and closes the circuit of relay 95. Relays 97 and 99 being slow acting maintain their armatures in an 130

energized position while their circuit is momentarily opened. When the first impulse is transmitted and the relay 96 de-energizes to repeat said impulse a circuit is closed which extends from ground G^{18} , through springs 129 and 130, springs 133 and the relay 95 to the battery B^3 . The relay 95 being slow acting maintains its armature in an energized position during the succeeding interruptions corresponding to the impulses of the group and in its energized position short circuits, at springs 156, the impedance 93 and upper winding of relay 94. A short time after the group of impulses have been transmitted the relay 95 again deenergizes and separates springs 156. During the time that relay 95 is energized, impulses are transmitted by the relay 96 to the connector line relay 63 over a circuit which extends from ground through the lower winding of line relay 63 through springs 147 and 148, line conductor 79, springs 132 of relay 96, springs 156 of relay 95, return line conductor 77, springs 149 and 150 and the upper winding of the line relay 63 to the battery B^3 . In response to interruptions of the above circuit, line relay 93 is momentarily deenergized a number of times; release relay 67, however, being slow acting, maintains its armature in the attracted position during momentary deenergizations of relay 63. Each time the line 63 deenergizes, an impulse of current is transmitted to the vertical magnet 64 over a circuit which extends from ground G^{21} , through spring 151 and its back contact, springs 153 and 154, private control relay 71, vertical magnet 64, side switch wiper 113 (in first position) to the battery B^3 . The vertical magnet receives two impulses over this circuit and operates to raise the shaft wipers 60, 61, and 62 two steps to a position opposite the second level of contacts. The relay 71 is energized by these impulses and operates to close a circuit extending from ground G^{22} , through springs 157 and the private magnet 70 to the battery B^3 . The relay 71, being slow acting does not allow its armature to fall back until after the last impulse has been delivered to the vertical magnet, when it breaks the circuit to the private magnet 70 which in turn deenergizes and permits the side switch to pass to the second position. The side switch wiper 113 in passing from first to second position transfers the battery connection from the vertical magnet 64 to the rotary magnet 65. The operator, at the cord circuit O, now operates the calling device 20 for the last digit 0, whereby the energizing circuit of the connector line relay 63 is broken ten times in the same manner as previously described. Each time the relay 63 deenergizes an impulse of current is transmitted

over a circuit extending from ground G²¹ through spring 151 and its back contact, springs 153 and 154, relay 71, springs 158 of relay 72, rotary magnet 65, side switch wiper 113, (in second position) to the battery B³. The rotary magnet operates in response to these impulses to step the wipers 60, 61, and 62 ten steps onto the contacts of the desired line, while the relay 71 operates in the same manner as for the previous digit to advance the side switch another step, *i. e.*, from second to third position, after the last impulse of the series is delivered. The movement of the side switch wipers 110 and 111 to third position completes the line connection with the called telephone. The wiper 112, upon reaching third position, establishes a guarding ground potential at the connector private bank contacts of the called line and also provides an energizing circuit for the cut-off winding 75 of the subscriber's individual switch C'. This circuit extends from ground G²⁴ through the side switch wiper 112, private wiper 61 and cut-off winding 75 to the battery B³. The cut-off winding, upon energizing, removes the line relay 76 from the called subscriber's line. The side switch wiper 113 on passing to third position completes the circuit of the ringing relay 69 which extends from ground G²⁵ through interrupter 74, ringing relay 69, springs 158 of relay 73, side switch wiper 113 (in third position) to the battery B³. The relay 69, upon energizing, operates to disconnect the calling line from the called line, and to bridge the ringing current generator R across the called line to signal the called subscriber. Since the circuit of the relay 69 includes the interrupter 74, said relay is energized only intermittently.

After having completed the call, the operator restores the key K (Fig. 2) to its normal position, whereby the calling device is disconnected from the trunk and the circuit of the polarized relay 18 is re-established. The relay 18 again energizes to close the circuit of supervisory signal 21 as hereinbefore stated. When the subscriber at the called telephone A³ removes his receiver, or as soon thereafter as the ringing relay 69 de-energizes, if it happens to be energized at the time, said telephone is provided with talking current over a circuit extending from ground through the left hand winding of the back bridge relay 66, springs 160 of private magnet 70, thence over heavy conductors to back contacts of ringing relay 69, line wiper 62 to and through the substation A³, back over the other side of the line to wiper 60, another set of back contacts of ringing relay 69, over heavy conductor to springs 161 of private magnet 70 and through the right

hand winding of the back bridge relay 66 to the battery B^3 . The relay 66, upon energizing, transposes the connections between the windings of the line relay 63 and the trunk conductors 77 and 79 whereby the direction of current flowing in the upper winding of relay 94 is reversed. This reversal of current in the upper winding of relay 94, causes said relay to attract its armature to shift spring 108 out of contact with spring 109 and into contact with spring 107, whereby the battery B^2 is inserted in series with the battery B (Fig. 2). These batteries have their opposite poles 10 grounded and will produce an increased flow of current which is sufficient to operatively energize the marginal relay 49 of repeater F. Relay 49, upon energizing, transposes the connections between the 15 windings of line relay 44 and the trunk line conductors 46 and 47, whereby the direction of current flowing in the trunk line is reversed. Polarized relay 18, being included in this circuit operates to open the 20 circuit of the supervisory signal 21 and the lamp is extinguished. In this manner the 25 operator is notified that the called man has answered.

A further result of the energization of 30 relay 66 upon the response of the called subscriber is the closing of a circuit to cut-off relay 73, which circuit extends from ground G^{24} through side switch wiper 112, springs 162 and the said relay 73 to the battery B^3 . 35 The relay 73, upon energizing, breaks the circuit of the ringing relay at springs 158 and closes a locking circuit for itself through its springs 159 independent of the springs 162 of relay 66, so that the ringing relay cannot be again energized until 40 the connector restores and makes another call.

The subscriber at the manual substation A^2 may now converse with the subscriber 45 at the automatic substation A^3 . The voice currents will travel over the heavy conductors and through repeating coils I and Z herein shown. After the conversation is completed the operator is given a disconnect 50 signal when the calling subscriber hangs up his receiver and another signal when the called subscriber hangs up. When the calling subscriber hangs up, his line circuit is broken at spring 7, thereby opening the circuit of relay 15 and coil 17. Relay 15, upon deenergizing, closes the circuit of supervisory lamp 19. When the called subscriber restores his receiver to the hook switch, the circuit of the back bridge relay 55 66 is broken. Upon the relay 66 deenergizing, the direction of current flow in the upper winding of relay 94 is reversed and is again in the proper direction to cause the windings of relay 94 to oppose each 60 65 other, whereby its armature is released,

causing the spring 108 to be shifted out of contact with spring 107 and into contact with spring 109. The booster battery B^2 is thereupon removed from the circuit of relays 96 of repeater F' and marginal relay 70 49 of repeater F. Relay 49, owing to its marginal adjustment, deenergizes and reverses the direction of current flow to the polarized relay 18, which operates to move its armature in the direction to close the 75 circuit of supervisory signal 21. The operator, perceiving the disconnect signals, removes the plugs P and P' from the jacks J and J'. By the removal of the plug P from jack J, the circuit of the cut-off relay 9 80 is broken. Relay 9, upon deenergizing, restores the central office equipment of the calling subscriber's line to its normal condition. By the removal of the plug P' from the jack J' the circuit of the line relay 44 85 of repeater F is broken, which relay, upon deenergizing, opens the circuit of relay 45 and also opens the circuit of relays 49 and 96 of repeaters F and F', respectively. Relay 45, upon deenergizing, removes the holding ground G^{12} from the release conductor 48 and from the relay 56. The relay 56, upon deenergizing, again bridges the drop relay 57 and condenser C⁴ across the trunk line and at springs 131 opens the circuit of 95 busy signal lamp 59. Upon the removal of ground from the release conductor 48 the switching relay 26 of selector E deenergizes and closes the release magnet circuit which extends from ground G^{10} through the contact of springs 172, springs 38, springs 173, off-normal springs 34 and the release magnet 25 to the battery B. The release magnet 25, upon energizing, restores the switch to its normal condition and its own circuit is 100 opened at springs 34 when the shaft reaches its lowest position. The relay 96, upon deenergizing, opens the bridge across the trunk conductors 77 and 79 by separating springs 132. A further result of the deenergization of relay 96 is the separation of 110 springs 129 and 131 and closure of springs 129 and 130, whereby relays 97 and 99 are deenergized. Relay 97, upon deenergizing, removes the repeating coil from across the 115 trunk conductors 77 and 79 and connects said coil with the contacts of selector banks, which conditions normally exist. Relay 99, upon deenergizing, opens the circuit of relay 95 which was closed when relay 96 deenergized and also by the separation of springs 134, 135, and 136 removes the guarding ground from the private contacts of the selector banks and opens the circuit of lower winding of relay 94. A further result of the deenergization of relay 99 is the opening of the circuit of relay 92 which, upon deenergizing, again bridged the drop relay 90 and condenser C⁷ across the trunk line 120 and, at springs 142, opens the circuit of the 125 130

busy signal lamp 89. When the relay 96 de-energizes and removes the bridge across the trunk line 77 and 79 by separating springs 132, the circuit of the line relay 63 of connector H is broken. The relay 63, upon de-energizing, opens the circuit of relay 67, which upon deenergizing, closes the circuit of the release magnet 68 which was closed at another point by relay 63. The energizing circuit of release magnet 68 extends from ground G²¹ through spring 151 and its back contact, springs 153 and 152, off-normal contact 114 and the release magnet 68 to the battery B³. The release magnet, upon energizing, restores the switch to its normal condition and its own circuit is opened at springs 114 when the switch shaft reaches its lowest position. The releasing of the connector opens the circuit of cut-off winding 75 of the called subscriber's individual switch C' which, upon deenergizing, again places the line relay 76 under control of the substation A³.

In the above description it was assumed that the called line was idle and that connector H completed connection therewith. It will now be explained how connection is prevented from being completed with a busy line and how the operator is given a busy signal. Whenever a line is busy, either on account of having made a call or on account of having been called, its connector private bank contacts are provided with a guarding ground potential. Therefore, when the private wiper 61 is rotated onto the contact of the busy line and as soon thereafter as the slow relay 71 deenergizes, a connection is completed from ground upon said contact through the wiper 61, side switch wiper 112 (in second position) springs 163 and 164, busy test relay 72, normally closed springs of relay 71, and the private magnet 70 to the battery B³. The private magnet 70 remains energized over this circuit and maintains the side switch wipers in second position, thereby preventing the connection to the busy called line. The busy relay 72, upon energizing, opens the circuit of the rotary magnet at springs 158, disconnects itself from the private wiper 61 and upon the engagement of its springs 165 and 164 completes a locking circuit for itself which extends from ground G²⁶ through off-normal contact 115, springs 165 and 164, relay 72, normally closed springs of relay 71 and the private magnet 70 to the battery B³. Upon the closure of springs 166, by the energization of relay 72, a circuit is completed including the busy signaling machine Q which may be traced over the following path: Ungrounded pole of battery B³, secondary winding 167 of the induction coil, springs 166, side switch wiper 111 (in second position), line conductor 79, springs 148 and 144 of relay 97, winding Z⁴ of repeating coil Z, condenser C⁶,

winding Z² of said repeating coil, springs 143 and 147, return line conductor 77, springs 149 and 150, upper winding of the line relay 63 to the ungrounded pole of battery B³, the starting point. The busy tone in passing through the repeating coil windings induces a tone in windings Z' and Z³ which flows over a circuit that extends from winding Z', contacts of jack J³, over toll line conductor 87, contacts of jack J², thence through windings I² and I⁴ of repeating coil I, contacts of jack J², along return toll line conductor 88, contacts of jack J³ and through winding Z³ to winding Z'. A busy tone is thus induced in windings I' and I³ of repeating coil I which flows from winding I' through springs 168 of relay 51, trunk conductor 46, line wiper 31, springs 170 of relay 26, tip of jack J' and tip of plug P', springs 41 and 42 of key K, through contacts of key K' to and through the operator's set, back over contacts 42' and 41', ring of plug P' and ring of jack J', springs 171 of relay 26, wiper 33, return trunk conductor 47, springs 169 of relay 51, winding I³ and condenser C⁶ to winding I'. The operator receives an audible buzz in her receiver over the above circuit and informs the calling subscriber that the called line is busy. The operator withdraws the plugs P and P' from the jacks J and J' which causes the release of the apparatus in a similar manner to that hereinbefore described.

It will be understood that I may provide telephone equipment arranged for measured service such as the automatic telephone equipment shown in British patent to Dicker, No. 1298 of 1910, or I may provide coin controlled telephone equipment such as the type shown in United States Letters Patent to B. D. Willis, No. 1,130,784, granted March 9, 1915. Either type of telephone shown in the aforesaid mentioned patents may be arranged in connection with a subscriber's individual switch (such as the switch C' herein shown and referred to as similar to that shown in United States Letters Patent to F. Newforth, Jr., No. 13,901, reissued April 13, 1915), to connect with a selector switch such as the type of switch herein represented at E. Such selectors, through their bank contacts, which are represented in Fig. 2, as 35, 36, and 37 and in Fig. 4 as 81, 82, and 83, may seize the repeater F or F' depending upon the direction of the call. Assuming that the repeater F is the one seized, the said repeater will then be responsive to the dial of the calling automatic subscriber in the same manner as that herein described with respect to the operator.

When the called man answers, battery will be reversed to the calling substation—if a measured service system—to register the meter—but if a coin controlled system—to render his telephone inoperative for talk-

ing purposes until the required coin or coins have been deposited. The release of the apparatus is controlled by the calling automatic subscriber in a manner similar to 5 that described with respect to the operator and aforesaid mentioned patents.

The jacks J^2 (Fig. 3) and J^3 (Fig. 4), shown at each end of the toll line 87 and 88 are for the purpose of providing means 10 whereby an operator at one end of the line may manually signal an operator at the other end. By inserting a plug into the jack J^2 the spring contacts 174 and 175 are opened, whereby the repeater is removed 15 from the line and is prevented from being seized because of a guarding ground potential being supplied from ground at G^{14} along release conductor 48 to the private bank contacts of the selectors adapted to 20 make connection therewith. When a plug, similar to the plug P of cord circuit O , whose sleeve conductor is connected to ground, is inserted into the jack J^2 a circuit is closed which extends from ground upon 25 the sleeve of the plug through sleeve of jack J^2 and the relay 58 to the battery. Relay 58, upon energizing, closes the before mentioned circuit from ground G^{14} by way of contact 176, armature 128, conductor 30 127, and release conductor 48 to the selector private bank contacts. Having inserted a plug in jack J^2 , the operator may project ringing current in the well known manner 35 out over the trunk line to actuate the drop 90 at the distant exchange, thereby signaling an operator there stationed. By plugging into the jack J^3 the called operator may converse with the calling operator and at the same time disconnect the automatic 40 apparatus as described in the case of jack J^2 . After having finished with the connection the operator withdraws the plugs and the circuit conditions are again restored so 45 that connection may be made in either direction manually, automatically or semi- automatically.

From the foregoing it is evident that I have devised a very efficient telephone system in which automatic connections are set 50 up and controlled over simplex circuits superimposed upon two way trunk lines.

Furthermore, it is obvious that I provide improved means responsive to the answering of the called subscriber for performing several functions, one of which is the controlling over a simplex circuit, of a supervisory signal at an operator's board when the connection is established by the operator through the medium of her calling device and the automatic switches. Another function is the controlling, over a simplex circuit, of measured service devices or coin collecting apparatus at a calling automatic substation, when the subscriber himself operates and controls the automatic switches. 65

While I have illustrated and described one particular embodiment of my invention, it is to be understood that I do not wish to be limited to the exact construction and arrangement of apparatus and circuits shown 70 and described, but that various modifications can be made without departing from the spirit and scope of my invention.

What I claim as my invention is:

1. In a telephone system, means for connecting calling and called lines including a trunk line and an automatic switch, an operating circuit for said switch including both sides of the talking conductors of said trunk line in multiple, a source of current 75 for said circuit, means controlled by a calling line for operating said switch over said circuit to connect with a called line, a relay, and means for operating said relay from the said called line by altering the 80 current flow in said circuit.

2. In a telephone system, two exchanges, circuits each having two branches, a two conductor trunk line inductively connected at each end to one of said circuits connecting 90 said exchanges, one of said branches of each circuit terminating in an automatic switch and the other terminating in a set of fixed terminals, an operating circuit for said switches including the two conductors 95 of said trunk line in parallel, a relay associated with each set of fixed terminals for controlling said operating circuit, a group of selector switches at each exchange adapted for seizing the set of fixed terminals thereat, 100 means at each exchange for controlling a selector switch in the group there located to seize the associated set of fixed terminals and for operating the relay associated therewith, whereby said automatic switch 105 at the other exchange may be operated through the medium of said operating circuit.

3. In a telephone system, two exchanges, circuits each having two branches, a two 110 conductor trunk line inductively connected at each end to one of said circuits connecting said exchanges, one of said branches of each circuit terminating in an automatic switch and the other terminating in a set of fixed 115 terminals, an operating circuit for said switches including the two conductors of said trunk line in parallel, a relay associated with each set of fixed terminals for controlling said operating circuit, a group of 120 selector switches at each exchange adapted for seizing the set of fixed terminals thereat, means at each exchange for controlling a selector switch in the group there located to seize the associated set of fixed terminals 125 and for operating the relay associated therewith, whereby said automatic switch at the other exchange may be operated through the medium of said operating circuit, and automatic means for disconnecting the other 130

automatic switch and for making the other set of fixed terminals busy to its associated group of selector switches.

4. In a telephone system, two exchanges, 5 circuits each having two branches, a two conductor trunk line inductively connected at each end to one of said circuits connecting said exchanges, one of said branches of each circuit terminating in an automatic 10 switch and the other terminating in a set of fixed terminals, an operating circuit for said switches including the two conductors of said trunk line in parallel, a relay for controlling said operating circuit associated 15 with each set of fixed terminals, a group of selector switches at each exchange, a manual switchboard associated with each exchange, and operator controlled means at each switchboard for operating a selector switch 20 in the associated exchange to seize the set of fixed terminals there located and for operating the relay associated therewith, whereby said automatic switch at the other exchange may be operated by way of said 25 operating circuit.
5. In a telephone system, two exchanges, a pair of circuits each having two branches, a two conductor trunk line inductively connected at each end to one of said circuits 30 connecting said exchanges, one of said branches of each circuit terminating in an automatic switch and the other terminating in a set of fixed terminals, an operating circuit for said switches including the 35 two conductors of said trunk line in parallel, a relay for controlling said operating circuit associated with each set of fixed terminals, a group of selector switches at each exchange, a manual switchboard associated 40 with each exchange, a supervisory signal at each switchboard, operator controlled means at each switchboard for operating a selector switch in the associated exchange to seize the set of fixed terminals there located and 45 for operating the relay associated therewith, whereby said automatic switch at the other exchange may be operated by way of said operating circuit, and means controlled over said operating circuit from either exchange 50 for operating the signal at the switchboard associated with the other exchange.

6. In a telephone system, automatic switches, two exchanges, a trunk line terminating at each end in one of said automatic 55 switches connecting said exchanges, a controlling circuit superimposed on said trunk line and having at each end a normally connected branch containing a relay for controlling the automatic switch at that end, a 60 source of current for said controlling circuit, circuits at each exchange adapted for connection to said trunk line, supervisory signals associated with said circuits, a normally disconnected branch at each end of said

controlling circuit containing a supervisory 65 control relay, means for connecting one of said circuits at either exchange with said trunk line, automatic means for then substituting the normally disconnected branch at that exchange for the normally connected 70 branch, means associated with the connected circuit at the one exchange for operating the controlling relay at the other exchange by way of said controlling circuit, a second source of current, and means at the said 75 other exchange for introducing said second source in the said controlling circuit to operate the supervisory control relay at the said first exchange.

7. In a telephone system, a calling and a 80 called line, means for connecting said lines including a trunk line and an automatic switch, an operating circuit for said switch including both sides of the talking conductors of said trunk line in multiple, a source 85 of current for said circuit, means controlled by the calling line for operating said switch over said circuit to connect with the called line, a relay for reversing the direction of current flow over the calling line, and means 90 associated with said circuit and controlled by the called line thereover for operating said relay.

8. In a telephone system, two exchanges each comprising a plurality of lines, a two 95 way trunk line between exchanges, said trunk line provided with an automatic switch at each end, a circuit including two conductors of said trunk line in parallel for controlling said switches, a source of 100 current for said circuit, means controlled by a calling line in one exchange for operating the automatic switch in the other exchange over said circuit to connect with a called line, a relay, and means associated 105 with said circuit and controlled by the called line thereover for operating said relay to reverse the direction of current in the calling line.

9. In a telephone system, a calling and a 110 called line, means for connecting said lines including a trunk line and an automatic switch, an operating circuit for said switch superimposed upon talking conductors of said trunk line, a source of current for said 115 circuit, means controlled by the calling line for operating said switch over said circuit to connect with the called line, a relay for reversing the direction of current flow over the calling line, means associated with said circuit for operating said relay, said relay 120 irresponsible to normal current in said circuit, said means for increasing the flow of current in said circuit to operate said relay.

10. In a telephone system, two exchanges each comprising a plurality of lines, a two way trunk line between exchanges, said trunk line provided with an automatic 125

switch at each end, a circuit including two conductors of said trunk line in parallel for controlling said switches, a source of current for said circuit, means controlled by a calling line in one exchange for operating the automatic switch in the other exchange over said circuit to connect with a called line, a relay associated with said circuit, said relay responsive to normal current in said circuit, said means for increasing the flow of current in said circuit to operate said relay.

11. In a telephone system, a calling and a called line, means for connecting said lines including a trunk line and an automatic switch, an operating circuit for said switch including both sides of the talking conductors of said trunk line in multiple, a source of current for said circuit, means controlled by the calling line for operating said switch over said circuit to connect with the called line, a relay for reversing the direction of current flow in the calling line, means associated with said circuit for operating said relay, said relay responsive to normal current in said circuit, a second source of current, said means controlled by the called line for including said second source in said circuit to operate said relay.

12. In a telephone system two exchanges each comprising a plurality of lines, a two way trunk line between exchanges, said trunk line provided with an automatic switch at each end, a circuit including two conductors of said trunk line in parallel for controlling said switches, a source of current for said circuit, means controlled by a calling line in one exchange for operating the automatic switch in the other exchange over said circuit to connect with a called line, a relay for reversing the direction of current flow over the calling line, means associated with said circuit for operating said relay, said relay responsive to normal current in said circuit, a second source of current, said means controlled by the called line for including said second source in said circuit to operate said relay.

13. In a telephone system, an operator's position and a trunk line accessible therewith, an automatic switch, a second trunk line terminating in said automatic switch, a third trunk inductively connecting the two, a circuit including two conductors of said third trunk line in parallel, a source of current for said circuit, means at the operator's position for controlling said circuit by way of said first trunk line, means in said circuit for controlling said switch by way of said second trunk line, a signal at said operator's position, and a relay in said circuit for controlling said signal.

14. In a telephone system, a calling line, an operator's position and a trunk line accessible therewith, means at the operator's

position for connecting said calling line and trunk line, a called line, an automatic switch, a second trunk line terminating in said automatic switch having access to said called line, a third trunk line inductively connecting said first and second trunk lines, a circuit including two conductors of said third trunk line in parallel, a source of current for said circuit, means in said circuit for controlling said switch by way of said second trunk line, means including said first trunk line for controlling said circuit from the operator's position, whereby said switch may be operated to connect with the called line, a signal at the operator's position, and a relay in said circuit for controlling said signal.

15. In a telephone system, an operator's position and a trunk line accessible therewith, an automatic switch, a second trunk line terminating in said automatic switch, a third trunk inductively connecting the two, a circuit including two conductors of said third trunk line in parallel, a source of current for said circuit, means at the operator's position for controlling said circuit by way of said first trunk line, means in said circuit for controlling said switch by way of said second trunk line, a signal at said operator's position, a relay in said circuit responsive to normal current therein for controlling said signal, and means for increasing the current flow in said circuit to operate said relay.

16. In a telephone system, a calling line, an operator's position and a trunk line accessible therewith, means at the operator's position for connecting said calling line and trunk line, a called line, an automatic switch, a second trunk line terminating in said automatic switch having access to said called line, a third trunk line inductively connecting said first and second trunk lines, a circuit including two conductors of said third trunk line in parallel, a source of current for said circuit, means in said circuit for controlling said switch by way of said second trunk line, means including said first trunk line for controlling said circuit from the operator's position, whereby said switch may be operated to connect with the called line, a signal at the operator's position, a relay in said circuit responsive to normal current therein for controlling said signal, and means for increasing the current flow in said circuit to operate said relay.

17. In a telephone system, an operator's position and a trunk line accessible therewith, an automatic switch, a second trunk line terminating in said automatic switch, a third trunk inductively connecting the two, a circuit including two conductors of said third trunk line in parallel, a source of current for said circuit, means at the operator's

- position for controlling said circuit by way of said first trunk line, means in said circuit for controlling said switch by way of said second trunk line, a signal at said operator's position, a relay in said circuit irresponsible to normal current therein for controlling said signal, a second source of current and means for including said second source in said circuit to increase the current flow therein to operate said relay.
18. In a telephone system, a calling line, an operator's position, and a trunk line accessible therefrom, means at the operator's position for connecting said calling line and trunk line, a called line, an automatic switch, a second trunk line terminating in said automatic switch having access to said called line, a third trunk line inductively connecting said first and second trunk lines, a circuit including two conductors of said third trunk line in parallel, a source of current for said circuit, means in said circuit for controlling said switch by way of said second trunk line, means including said first trunk line for controlling said circuit from the operator's position, whereby said switch may be operated to connect with the called line, a signal at the operator's position, a relay in said circuit irresponsible to normal current therein for controlling said signal, and means for increasing the current flow in said circuit to operate said relay, said last means including a relay in bridge of said second trunk line.
19. In a telephone system, a calling line, an operator's position, and a trunk line accessible therefrom, means at the operator's position for connecting said calling line and trunk line, a called line, an automatic switch, a second trunk line terminating in said automatic switch having access to said called line, a third trunk line inductively connecting said first and second trunk lines, a circuit including two conductors of said third trunk line in parallel, a source of current for said circuit, means in said circuit for controlling said switch by way of said second trunk line, means including said first trunk line for controlling said circuit from the operator's position, whereby said switch may be operated to connect with the called line, a signal at the operator's position, a relay in said circuit irresponsible to normal current therein for controlling said signal, and means for increasing the current flow in said circuit to operate said relay.
20. In a telephone system, an operator's position and a trunk line accessible therefrom, an automatic switch, a second trunk line terminating in said automatic switch, a third trunk line inductively connecting the two, a circuit including two conductors of said third trunk line in parallel, a source of current for said circuit, means at the operator's position for controlling said circuit by way of said first trunk line, means in said circuit for controlling said switch by way of said second trunk line, a signal at said operator's position, a relay in said circuit irresponsible to normal current therein for controlling said signal, and means for increasing the current flow in said circuit to operate said relay, said last means including a relay in bridge of said second trunk line.
21. In a telephone system, a calling line, an operator's position and a trunk line accessible therefrom, means at the operator's position for connecting said calling line and trunk line, a called line, an automatic switch, a second trunk line terminating in said automatic switch having access to said called line, a third trunk line inductively connecting said first and second trunk lines, a circuit including two conductors of said third trunk line in parallel, a source of current for said circuit, means in said circuit for controlling said switch by way of said second trunk line, means including said first trunk line for controlling said circuit from the operator's position, whereby said switch may be operated to connect with the called line, a signal at the operator's position, a relay in said circuit irresponsible to normal current therein for controlling said signal, and means controlled from the connected called line for increasing the current flow in said circuit to operate said relay.
22. In a telephone system, means for connecting calling and called lines comprising a trunk line having an automatic switch at both ends, an operating circuit for said switches superimposed upon talking conductors of said trunk line, a source of current for said circuit, means controlled by an operator for connecting a calling line with said trunk line at either end, means controlled by said operator for operating said switch at the other end to connect with a called line, a supervisory signal for indicating to said operator the condition of the said called line, normally inoperative means in said circuit for controlling said signal, and means for increasing the current flow in said circuit to operate said signal controlling means.
23. In a telephone system, means for connecting calling and called lines comprising a trunk line having an automatic switch at both ends, an operating circuit for said switches superimposed upon talking conductors of said trunk line, a source of current for said circuit, means controlled by an operator for connecting a calling line with said trunk line at either end, means controlled by said operator for operating said switch at the other end to connect with a called line, a supervisory signal for indicating to said operator the condition of the said called line, normally inoperative means in said circuit for controlling said signal, and means for increasing the current flow in said circuit to operate said signal controlling means.

- line, a supervisory signal for indicating to said operator the condition of the said called line, normally inoperative means in said circuit for controlling said signal, a second 5 source of current and means for including said second source in said circuit to increase the current flow therein to operate said signal controlling means.
24. In a telephone system, means for connecting calling and called lines comprising a trunk line having an automatic switch at both ends, an operating circuit for said switches superimposed upon talking conductors of said trunk line, a source of current 10 for said circuit, means controlled by an operator for connecting a calling line with said trunk line at either end, means controlled by said operator for operating said switch at the other end to connect with a called 15 line, a supervisory signal for indicating to said operator the condition of the said called line, normally inoperative means in said circuit for controlling said signal, and means controlled from the connected called line for 20 increasing the current flow in said circuit to operate said signal controlling means.
25. In a trunking system, a pair of conductors, a first bridge across said conductors, a second bridge across said conductors, 25 means for closing a third bridge across said first and second bridges, a source of current included in said third bridge, a first relay associated with said third bridge, a line, an automatic progressively movable switch, 30 means for controlling said first relay over said third bridge to operate said switch to find said line, a second relay associated with said third bridge, a signal associated with said second relay, said second relay normally 35 inoperative, a second source of current and means controlled over said line for introducing said second source in said third bridge whereby said second relay may be 40 operated to control said signal.
45. 26. In a trunking system, a pair of conductors, a first bridge across said conductors, a second bridge across said conductors, means for closing a third bridge across said first and second bridges, a source of current 50 in said third bridge, a first line, a second line, means controlled over the first line for controlling said first relay over said third bridge to operate said switch to connect the two lines by way of said conductors, a second 55 relay associated with said third bridge, a signal associated with said second relay, said second relay normally inoperative, a second source of current and means controlled over said second line for introducing said second source in said third bridge whereby said second relay may be 60 operated to control said signal.
65. 27. In a telephone trunking system, a first circuit and a first automatic switch associated therewith, a second circuit and a second automatic switch associated therewith, a two conductor trunk line inductively connecting said circuits, a third circuit including the two conductors of said trunk line in parallel, a source of current for said 70 circuits, a relay in the third circuit at one end for controlling said first switch, a relay in the third circuit at the other end for controlling said second switch, relays in the first and second circuits for controlling the 75 third circuit, supervisory signals associated with said first and second circuits, supervisory control relays associated with said first and second circuits and adapted for inclusion in said third circuit, and means for closing said first circuit to operate the relay included therein whereby the third circuit is completed by way of the supervisory control relay for the first circuit and the controlling relay for the second switch. 80
85. 28. In a telephone trunking system, a first circuit and a first automatic switch associated therewith, a second circuit and a second automatic switch associated therewith, a two conductor trunk line inductively connecting said circuits, a third circuit including the two conductors of said trunk line in parallel, a source of current for said 90 circuits, a relay in the third circuit at one end for controlling said first switch, a relay in the third circuit at the other end for controlling said second switch, relays in the first and second circuits for controlling the 95 third circuit, supervisory signals associated with said first and second circuits, supervisory control relays associated with said first and second circuits and adapted for inclusion in said third circuit, and means for closing said second circuit to operate the relay included therein whereby the third circuit is completed by way of the supervisory control relay for the second circuit and the controlling relay for the first switch. 100
105. 29. In a telephone trunking system, a first circuit and a first automatic switch associated therewith, a second circuit and a second automatic switch associated therewith, a two conductor trunk line inductively connecting said circuits, a third circuit including the two conductors of said trunk line in parallel, a source of current for said 110 circuits, a relay in the third circuit at one end for controlling said first switch, a relay in the third circuit at the other end for controlling said second switch, relays in the first and second circuits for controlling the 115 third circuit, supervisory signals associated with said first and second circuits, supervisory control relays associated with said first and second circuits and adapted for inclusion in said third circuit, and means for closing either said first circuit or said second circuit to operate the relay included 120
- 125.

therein, whereby the third circuit is completed by way of the supervisory control relay for the circuit closed and the controlling relay for the switch associated with 5 the other circuit.

30. In a telephone trunking system, a first circuit and a first automatic switch associated therewith, a second circuit and a second automatic switch associated therewith, a two conductor trunk line inductively connecting said circuits, a third circuit including the two conductors of said trunk line in parallel, a source of current for said circuits, a relay in the third circuit at one end 10 for controlling said first switch, a relay in the third circuit at the other end for controlling said second switch, relays in the first and second circuits for controlling the third circuit, supervisory signals associated with 15 said first and second circuits, supervisory control relays associated with said first and second circuits and adapted for inclusion in said third circuit, means for closing said first circuit to operate the relay included 20 therein whereby the third circuit is completed by way of the supervisory control relay for the first circuit and the controlling relay for the second switch, and means in the first circuit for intermittently interrupting the same whereby said second switch 25 may be operated.

31. In a telephone trunking system, a first circuit and a first automatic switch associated therewith, a second circuit and a second automatic switch associated therewith, a two conductor trunk line inductively connecting said circuits, a third circuit including the two conductors of said trunk line in parallel, a source of current for said 35 circuits, a relay in the third circuit at one end for controlling said first switch, a relay in the third circuit at the other end for controlling said second switch, relays in the first and second circuits for controlling the 40 third circuit, supervisory signals associated with said first and second circuits, supervisory control relays associated with said first and second circuits and adapted for inclusion in said third circuit, means for closing said second circuit to operate the relay included 45 therein whereby the third circuit is completed by way of the supervisory control relay for the second circuit and the controlling relay for the first switch, and means in the second circuit for interrupting the same whereby said first switch 50 may be operated.

32. In a telephone trunking system, a first circuit and a first automatic switch associated therewith, a second circuit and a second automatic switch associated therewith, a two conductor trunk line inductively connecting said circuits, a third circuit including the two conductors of said trunk line 55

in parallel, a source of current for said circuits, a relay in the third circuit at one end for controlling said first switch, a relay in the third circuit at the other end for controlling said second switch, relays in the first and second circuits for controlling the 65 third circuit, supervisory signals associated with said first and second circuits, supervisory control relays associated with said first and second circuits and adapted for inclusion in said third circuit, means for closing either said first circuit or said second circuit to operate the relay included therein, whereby the third circuit is completed by way of the supervisory control relay for the 70 circuit closed and the controlling relay for the switch associated with the other circuit, and means for interrupting the closed first or second circuit whereby the said second or first switch may be operated.

33. In a telephone trunking system, a first circuit and a first automatic switch associated therewith, a second circuit and a second automatic switch associated therewith, a two conductor trunk line inductively connecting said circuits, a third circuit including the two conductors of said trunk line in parallel, a source of current for said circuits, a relay in the third circuit at one end for controlling said first switch, a relay in the third circuit at the other end for controlling said second switch, relays in the first and second circuits for controlling the third circuit, supervisory signals associated with said first and second circuits, supervisory control relays associated with said first and second circuits and adapted for inclusion in said third circuit, means for closing said first circuit to operate the relay included therein whereby the third circuit is completed by way of the supervisory control relay for the first circuit and the controlling relay for the second switch, said supervisory control relay remaining inoperative, means in the first circuit for intermittently interrupting the same whereby 90 100 105 110 115 120 125 said second switch may be operated, and means in the controlling circuit of the second switch for increasing the flow of current in the third circuit to operate said supervisory control relay.

34. In a telephone trunking system, a first circuit and a first automatic switch associated therewith, a second circuit and a second automatic switch associated therewith, a two conductor trunk line inductively connecting said circuits, a third circuit including the two conductors of said trunk line in parallel, a source of current for said circuits, a relay in the third circuit at one end for controlling said first switch, a relay in the third circuit at the other end for controlling said second switch, relays in the first and second circuits for controlling the

third circuit, supervisory signals associated with said first and second circuits, supervisory control relays associated with said first and second circuits and adapted for inclusion in said third circuit, means for closing said second circuit to operate the relay included therein whereby the third circuit is completed by way of the supervisory control relay for the second circuit and the controlling relay for the first switch, said supervisory control relay remaining inoperative, means in the second circuit for interrupting the same whereby said first switch may be operated, and means in the controlling circuit of the first switch for increasing the flow of current in the third circuit to operate said supervisory control relay.

35. In a telephone trunking system, a first circuit and a first automatic switch associated therewith, a second circuit and a second automatic switch associated therewith, a two conductor trunk line inductively connecting said circuits, a third circuit including the two conductors of said trunk line in parallel, a source of current for said circuits, a relay in the third circuit at one end for controlling said first switch, a relay in the third circuit at the other end for controlling said second switch, relays in the first and second circuits for controlling the third circuit, supervisory signals associated with said first and second circuits, supervisory control relays associated with said first and second circuits and adapted for inclusion in said third circuit, means for closing said first circuit to operate the relay included therein whereby the third circuit is completed by way of the supervisory control relay for the first circuit and the controlling relay for the second switch, said supervisory control relay remaining inoperative, means in the first circuit for intermittently interrupting the same whereby said second switch may be operated, and means including a relay in the second switch for increasing the flow of current in said

*third circuit to operate said supervisory control relay.

36. In a telephone trunking system, a first circuit and a first automatic switch associated therewith, a second circuit and a second automatic switch associated therewith, a two conductor trunk line inductively connecting said circuits, a third circuit including the two conductors of said trunk line in parallel, a source of current for said circuits, a relay in the third circuit at one end for controlling said first circuit, a relay in the third circuit at the other end for controlling said second switch, relays in the first and second circuits for controlling the third circuit, supervisory signals associated with said first and second circuits, supervisory control relays associated with said first and second circuits and adapted for in-

clusion in said third circuit, means for closing said second circuit to operate the relay included therein whereby the third circuit is completed by way of the supervisory control relay for the second circuit and the controlling relay for the first switch, said supervisory control relay remaining inoperative, means in the second circuit for interrupting the same whereby said first switch may be operated, and means including a relay in the first switch for increasing the flow of current in said third circuit to operate said supervisory control relay.

37. In a telephone trunking system, a first circuit and a first automatic switch associated therewith, a second circuit and a second automatic switch associated therewith, a two conductor trunk line inductively connecting said circuits, a third circuit including the two conductors of said trunk line in parallel, a source of current for said circuits, a relay in the third circuit at one end for controlling said first circuit, a relay in the third circuit at the other end for controlling said second switch, relays in the first and second circuits for controlling the third circuit, supervisory signals associated with said first and second circuits, supervisory control relays associated with said first and second circuits and adapted for inclusion in said third circuit, means for closing either said first circuit or said second circuit to operate the relay included therein, whereby the third circuit is completed by way of the supervisory control relay for the circuit closed and the controlling relay for the switch associated with the other circuit, said supervisory control relay remaining inoperative, means for interrupting the closed first or second circuit whereby the said second or first switch may be operated, and means including a relay in the operated first or second switch for altering the current flow in said third circuit to operate said supervisory control relay.

38. In a trunking system, a first circuit, a second circuit, a trunk line inductively connecting said circuits, a third circuit including the two conductors of said trunk line in parallel, a source of current for said circuits, a relay in said first circuit for controlling said third circuit, a second relay in said third circuit for controlling said second circuit, a signal associated with said first circuit, and means including a third relay in said third circuit for controlling said signal.

39. In a trunking system, a first circuit, an automatic progressively movable switch, a second circuit including a controlling magnet for said switch, a trunk line inductively connecting said circuits, a third circuit including the two conductors of said trunk line in parallel, a source of current for said

circuits, a relay in said first circuit for controlling said third circuit, a second relay in said third circuit for controlling said second circuit, a signal associated with said first circuit, and means including a third relay in said third circuit for controlling said signal.

40. In a trunking system, a first circuit, a second circuit, a trunk line inductively connecting said circuits, a third circuit including the two conductors of said trunk line in parallel, a source of current for said circuits, a relay in said first circuit for controlling said third circuit, a second relay in said third circuit for controlling said second circuit, a signal associated with said first circuit, a third relay in said first circuit for controlling said signal, and means including a fourth relay in said third circuit for altering the current flow in said first circuit for controlling said third relay.

41. In a trunking system, a first circuit, an automatic progressively movable switch, a second circuit including a controlling magnetic net for said switch, a trunk line inductively connecting said circuits, a third circuit including the two conductors of said trunk line in parallel, a source of current for said circuits, a relay in said first circuit for controlling said third circuit, a second relay in said third circuit for controlling said second circuit, a signal associated with said first circuit, a third relay in said first circuit for controlling said signal, and means including a fourth relay in said third circuit for altering the current flow in said first circuit for controlling said third relay.

42. In a trunking system, a first circuit, a second circuit, a trunk line inductively connecting said circuits, a third circuit including the two conductors of said trunk line in parallel, a source of current for said circuits, a relay in said first circuit for controlling said third circuit, a second relay in 40 said third circuit for controlling said second circuit, a signal associated with said first circuit, a third relay in said first circuit for controlling said signal, means including a fourth relay in said third circuit 45 for altering the current flow in said first circuit for controlling said third relay, and a fifth relay in said second circuit for altering the current flow in said third circuit for 50 controlling said fourth relay.

55 43. In a trunking system, a first circuit, an automatic progressively movable switch, a second circuit including a controlling magnet for said switch, a trunk line inductively connecting said circuits, a third circuit including the two conductors of said trunk line in parallel, a source of current for said circuits, a relay in said first circuit for controlling said third circuit, a second relay in said third circuit for controlling said sec-

ond circuit, a signal associated with said first circuit, a third relay in said first circuit for controlling said signal, means including a fourth relay in said third circuit for altering the current flow in said first circuit for controlling said third relay, and a fifth relay in said second circuit for altering the current flow in said third circuit for controlling said fourth relay. 65 70

44. In a trunking system, a first circuit, a second circuit, a trunk line inductively connecting said circuits, a third circuit including the two conductors of said trunk line in parallel, a source of current for said circuits, a relay in said first circuit for controlling said third circuit, a second relay in said third circuit for controlling said second circuit, a signal associated with said first circuit, means including a third relay in said third circuit for controlling said signal, a second source of current and means for introducing said second source in said third circuit to alter the current flow therein to operate said third relay. 75 80 85 90

45. In a trunking system, a first circuit, an automatic progressively movable switch, 90 a second circuit including a controlling magnet for said switch, a trunk line inductively connecting said circuits, a third circuit including the two conductors of said trunk line in parallel, a source of current for said 95 circuits, a relay in said first circuit for controlling said third circuit, a second relay in said third circuit for controlling said second circuit, a signal associated with said first circuit, means including a third relay 100 in said third circuit for controlling said signal, a second source of current and means for introducing said second source in said third circuit to alter the current flow therein to operate said third relay. 105

46. In a trunking system, a first circuit, a second circuit, a trunk line inductively connecting said circuits, a third circuit including the two conductors of said trunk line in parallel, a source of current for said circuits, a relay in said first circuit for controlling said third circuit, a second relay in said third circuit for controlling said second circuit, a signal associated with said first circuit, means including a third relay in said third circuit for controlling said signal, a second source of current and means for introducing said second source in said third circuit to alter the current flow therein to operate said third relay, said last means comprising a relay in said second circuit. 110 115 120

47. In a trunking system, a first circuit, an automatic progressively movable switch, a second circuit including a controlling magnet for said switch, a trunk line inductively connecting said circuits, a third circuit including the two conductors of said trunk line in parallel, a source of current for said

- circuits, a relay in said first circuit for controlling said third circuit, a second relay in said third circuit for controlling said second circuit, a signal associated with said 5 first circuit, means including a third relay in said third circuit for controlling said signal, a second source of current and means for introducing said second source in said third circuit to alter the current flow therein 10 to operate said third relay, said last means comprising a relay in said second circuit.
48. In a trunking system, a first circuit, a second circuit, a trunk line inductively connecting said circuits, a third circuit including the two conductors of said trunk line in parallel, a source of current for said circuits, a relay in said first circuit for controlling said third circuit, a second relay in said third circuit for controlling said second 15 circuit, a signal associated with said first circuit, a third relay in said first circuit operated by reversing the direction of current flow therein for controlling said signal, and a fourth relay in said third circuit for reversing the direction of current flow in said first circuit.
49. In a trunking system, a first circuit, an automatic progressively movable switch, a second circuit including a controlling magnet for said switch, a trunk line inductively connecting said circuits, a third circuit including the two conductors of said trunk line in parallel, a source of current for said circuits, a relay in said first circuit for controlling said third circuit, a second relay in said third circuit for controlling said second circuit, a signal associated with said first circuit, a third relay in said first circuit operated by reversing the direction of current 20 flow therein for controlling said signal, and a fourth relay in said third circuit for reversing the direction of current flow in said first circuit.
50. In a trunking system, a first circuit, a second circuit, a trunk line inductively connecting said circuits, a third circuit including the two conductors of said trunk line in parallel, a source of current for said circuits, a relay in said first circuit for controlling said third circuit, a second relay in said third circuit for controlling said second circuit, a signal associated with said first circuit, a third relay in said first circuit operated by reversing the direction of current 25 flow therein for controlling said signal, a fourth relay in said third circuit for reversing the direction of current flow in said first circuit.
51. In a trunking system, a first circuit, an automatic progressively movable switch, a second circuit including a controlling magnet for said switch, a trunk line inductively connecting said circuits, a third circuit including the two conductors of said trunk line in parallel, a source of current for said circuits, a relay in said first circuit for controlling said third circuit, a second relay in said third circuit for controlling said second circuit, a signal associated with said first circuit, a third relay in said first circuit operated by reversing the direction of current 30 flow therein for controlling said signal, a fourth relay in said third circuit for reversing the direction of current flow in said first circuit.
52. In a trunking system, a first circuit, a second circuit, a trunk line inductively connecting said circuits, a third circuit including the two conductors of said trunk line in parallel, a source of current for said circuits, a relay in said first circuit for controlling said third circuit, a second relay in said third circuit for controlling said second circuit, a signal associated with said first circuit, a third relay in said first circuit operated by reversing the direction of current flow therein for controlling said signal, a fourth relay in said third circuit for reversing the direction of current flow in said third circuit, said fourth relay normally inoperative, a second source of current, and means for including said second source in said third circuit to increase the current flow therein to operate said fourth relay.
53. In a trunking system, a first circuit, an automatic progressively movable switch, a second circuit including a controlling magnet for said switch, a trunk line inductively connecting said circuits, a third circuit including the two conductors of said trunk line in parallel, a source of current for said circuits, a relay in said first circuit for controlling said third circuit, a second relay in said third circuit for controlling said second circuit, a signal associated with said first circuit, a third relay in said first circuit operated by reversing the direction of current flow therein for controlling said signal, a fourth relay in said third circuit for reversing the direction of current flow in said first circuit, said fourth relay normally inoperative, a second source of current, and means for including said second source in said third circuit to increase the current flow therein to operate said fourth relay, said last means comprising a relay in said second circuit.
54. In a trunking system, a first circuit, an automatic progressively movable switch, a

second circuit including a controlling magnet for said switch, a trunk line inductively connecting said circuits, a third circuit including the two conductors of said trunk line 5 in parallel, a source of current for said circuits, a relay in said first circuit for controlling said third circuit, a second relay in said third circuit for controlling said second circuit, a signal associated with said first circuit, a device associated with said first circuit for operating said switch through the medium of said first and second relays, and means including a normally inoperative 10 third relay in said third circuit for controlling said signal.

55. In a trunking system, a first circuit, an automatic progressively movable switch, a second circuit including a controlling magnet for said switch, a trunk line inductively connecting said circuits, a third circuit including the two conductors of said trunk line in parallel, a source of current for said circuits, a relay in said first circuit for controlling said third circuit, a second 20 relay in said third circuit for controlling said second circuit, a signal associated with said first circuit, a device associated with said first circuit for operating said switch through the medium of said first and second relays, means including a normally inoperative third relay in said third circuit for controlling said signal, and means controlled from said second circuit for increasing the current flow in said third circuit to 30 operate said third relay.

56. In a telephone system, two exchanges each comprising a plurality of lines, a two way trunk line between exchanges, said trunk line provided with an automatic switch at each end, a circuit including two conductors of said trunk line in parallel for controlling said switches, a source of current for said circuit, means controlled by a calling line in one exchange for operating 40 the automatic switch in the other exchange over said circuit to connect with a called line, a relay for reversing the direction of current flow over the calling line, means in said other exchange associated with said circuit for operating said relay, said relay 45 irresponsible to normal current in said circuit, said means controlled by the called line for increasing the flow of current in said circuit to operate said relay.

55. 57. In a telephone system, a plurality of exchanges each comprising a plurality of lines, two way trunk lines between exchanges, said trunk lines provided with an automatic switch at each end, an operating circuit for 60 said switches superimposed upon the talking conductors of said trunk lines, a source of current for said circuit, another trunk line, means controlled by a calling line in one exchange for operating the automatic switch

in another exchange over said circuit to 65 connect with a called line over said other trunk line, a first relay for reversing the direction of current flow over the calling line, a second relay associated with said circuit for increasing the flow of current in 70 said circuit, said first relay irresponsible to normal current in said circuit, a third relay associated with said other trunk line controlled over the called line for reversing the direction of current flow in said other trunk line, said second relay controlled by the reversal of current flow in said other trunk line for increasing the flow of current in 75 said circuit to operate said first relay.

58. In a telephone system, a plurality of exchanges each comprising a plurality of lines, two way trunk lines between exchanges, said trunk lines provided with an automatic switch at each end, an operating circuit for 80 said switches superimposed upon the talking conductors of said trunk lines, a source of current for said circuit, another trunk line, means controlled by a calling line in one exchange for operating the automatic switch in another exchange over said circuit to connect with a called line over said other trunk line, a first relay for reversing the direction of current flow over the calling line, a second relay associated with said circuit for 85 increasing the flow of current in said circuit, said first relay irresponsible to normal current in said circuit, a third relay associated with said other trunk line controlled over the called line for reversing the direction of current flow in said other trunk line, said second relay controlled by the reversal of current flow in said other trunk line for increasing the flow of current in 90 said circuit to operate said first relay.

59. In a telephone system, a plurality of exchanges each comprising a plurality of lines, two way trunk lines between exchanges, said trunk lines provided with an automatic switch at each end, an operating circuit for 100 said switches superimposed upon the talking conductors of said trunk lines, a source of current for said circuit, another trunk line, means controlled by a calling line in one exchange for operating the automatic switch in another exchange over said circuit to connect with a called line over said other trunk line, a first relay for reversing the direction of current flow over the calling line, a second relay associated with said circuit for 105 increasing the flow of current in said circuit, said first relay irresponsible to normal current in said circuit, a third relay associated with said other trunk line controlled over the called line for reversing the direction of current flow in said other trunk line, said second relay controlled by the reversal of current flow in said other trunk line for increasing the flow of current in said circuit to operate said first relay, said third relay supplying talking battery to the called line.

59. In a telephone system, a plurality of exchanges each comprising a plurality of lines, two way trunk lines between exchanges, said trunk lines provided with an automatic switch at each end, an operating circuit for 110 said switches superimposed upon the talking conductors of said trunk lines, a source of current for said circuit, another trunk line, means controlled by a calling line in one exchange for operating the automatic switch in another exchange over said circuit to connect with a called line over said other trunk line, a first relay for reversing the direction of current flow over the calling line, a second relay associated with said circuit for 115 increasing the flow of current in said circuit, said first relay irresponsible to normal current in said circuit, a third relay associated with said other trunk line controlled over the called line for reversing the direction of current flow in said other trunk line, said second relay having a winding in bridge of said other trunk line and con-

trollable thereover for increasing the flow of current in said circuit to operate said first relay.

60. In a telephone system, an operator's position and a trunk line, a first circuit associated with said operator's position, a signal for said circuit, a relay in bridge of said first circuit, said signal under the control of said first relay, a second circuit including 10 the two sides of said trunk line in parallel,

a source of current for said second circuit, a relay in said second circuit irresponsive to normal current in said circuit, said second relay controlling the operation of said first relay whereby said signal may be operated 15 over said second circuit.

Signed by me at Chicago, Cook county, Illinois this 23 day of Feb., 1916.

BERNARD D. WILLIS.
